FAN STAND

John R. Dean, Memphis, Tenn., assignor to Robbins & Myers, Inc., Springfield, Ohio, a corporation of Ohio

Continuation of design applications Ser. No. 86,544 and Ser. No. 86,546, Aug. 12, 1965. This application June 22, 1966, Ser. No. 5,175

Term of patent 3½ years

(Cl. D62—4)

FIG-5

FIG-7

FIG-6

FIG-8

FIGURE 1 is a perspective view of a fan stand showing my new design.

FIGURE 2 is a side view thereof.

FIGURE 3 is a front view thereof.

FIGURE 4 is a top view thereof.

FIGURE 5 is a perspective view of another fan stand of this invention.

FIGURE 6 is a top view of the fan stand of FIGURE 5.

FIGURE 7 is a front view of the fan stand of FIGURE 5.

FIGURE 8 is a side view of the fan stand of FIGURE 5.

The broken line showing of a fan in FIGURES 1 and 5 is for illustrative purposes only.

This application is a continuation of my copending design patent applications Ser. Nos. D. 86,544 and D. 86,546 both filed Aug. 12, 1965, and now abandoned.

I claim:

The ornamental design for a fan stand, substantially as shown and described.
